BELT

Melvin Zakarin, 23 Ogden Lane,
Englishtown, N.J. 07726

Filed July 22, 1970, Ser. No. 24,060

Term of patent 3½ years

Int. Cl. D2—07

U.S. Cl. D2—385

Fig. 1.

Fig. 2.

Fig. 3.

FIG. 1 is a front isometric view of a belt showing my new design, the design of the belting continuing around the back;

FIG. 2 is a top plan view of the belt;

FIG. 3 is an inside front elevation view thereof, shown broken away for convenience of illustration.

I claim:

The ornamental design for a belt, substantially as shown and described.
